COMBINED BACK AND HEAD REST ATTACHMENT FOR AN AUTOMOBILE SEAT

Nicholas Gianvecchio, 82 Woodrow Ave.,
Toronto, Ontario, Canada

Filed Nov. 30, 1962, Ser. No. 72,673

Term of patent 7 years

(Cl. D15—8)

FIG. 1

FIG. 2

FIG. 3

FIG. 1 is a front perspective view of the combined back and head rest attachment for an automobile seat;

FIG. 2 is a rear perspective view of the combined back and head rest attachment for an automobile seat;

FIG. 3 is an edge view thereof.

I claim:

The ornamental design for a combined back and head rest attachment for an automobile seat, as shown.
